DRILL SHARPENER

Gustav C. Pearson, Denver, Colo., assignor to
 Gardner-Denver Company, Denver, Colo., a
 corporation of Delaware

Application August 24, 1934, Serial No. 741,324

6 Claims. (Cl. 76—5)

The present invention relates to improvements in metal working machines, and is more specifically directed to pneumatically operated machines for shaping and sharpening drill steels.

5 The main object of the invention is to provide a motive fluid operated machine having two independent motors for performing separate and coacting operations upon the steel, the operation of one being dependent upon the operation of the other.

10 A further object of the invention lies in the provision of a motive fluid actuated sharpener comprising a forging cylinder and a clamping cylinder, having therein a common piston, and means for controlling the flow of motive fluid into both cylinders, either independently into the forging cylinder or successively into both.

15 Still another object of the invention lies in the provision of a second fluid operated tool for upsetting the work held in the sharpener during its clamping operation and the admission of motive fluid to the second tool being supplied from the clamping cylinder either after or during the clamping operation.

20 This application is a continuation in part of applicant's co-pending application, Serial No. 510,980, filed Jan. 24, 1931, now Patent No. 2,001,689, issued May 14, 1935, relating to "Drill sharpeners."

25 Further objects of the invention will be apparent from the description made hereinafter, and to all of these ends the invention consists of the features of construction, arrangement of parts, and combination of elements, substantially as hereinafter fully described in the specification, claimed and shown in the accompanying drawings in which:

30 Figure 1 is a side elevation of a fluid operated drill steel sharpener showing the control valve together with a fragmentary portion, in elevation, of a second fluid operated work engaging tool positioned thereupon.

35 Figure 2 is a vertical sectional view on the line 2—2 of Figure 1.

40 Figure 3 is a vertical sectional view, partly in elevation, taken on the line 3—3 of Figure 2.

45 Figure 4 shows a fragmentary portion of the drill sharpener with the second fluid operated work engaging tool mounted thereon, both being shown in section.

50 Figure 5 is a vertical sectional view on the line 5—5 of Figure 4.

55 Figure 6 is a horizontal sectional view on the line 6—6 of Figure 2.

55 Figure 7 illustrates a side elevation of the

main cylinder showing that portion to which the fluid control valve is secured.

Figure 8 is a vertical sectional view taken on the line 8—8 of Figure 6 showing the main passage for motive fluid from the control valve to the upper face of the large or forging piston. 5

Figure 9 is a view somewhat similar to Figure 8 taken on the line 9—9 of Figure 6 showing the passage for motive fluid from the control valve to the upper face of the smaller or clamping 10 piston, and

Figure 10 shows a section of a fragmentary portion of the main cylinder with the exhaust passage formed therein and communicating with a similar passage in the base leading to the ex- 15 haust chamber.

Briefly, the invention herein about to be described is directed to a drill sharpening unit which includes two separate, but coacting, fluid operated work engaging elements. One of said 20 elements constitutes the means for performing the necessary forging and clamping operations necessary in the sharpening of a drill steel. This element includes a pair of cylinders arranged in tandem with a piston in each cylinder. 25 The pistons are connected by a piston rod and movable in unison by motive fluid active upon one of said pistons when performing the forging operation or upon both when clamping the steel during the operation of the second fluid operated 30 work engaging element. This second fluid operated work engaging element is mounted upon the first and performs certain operations upon the steel during the functioning period of the first work engaging element. This second work 35 engaging element is hereinafter referred to as a dolly hammer and dolly hammer cylinder, and the dolly hammer, when set in operation, upsets the steel firmly clamped by the first work engaging element. 40

Heretofore in sharpeners of this type it has been customary to provide three distinctive forward movements for the control handle of the motive fluid valve which supplies fluid to the sharpener and to the upsetting tool. Applicant 45 simplifies this by providing a mechanism which necessitates only two forward movements of the handle, and during such movements the operation of the upsetting tool is prevented until at such time when the steel has been firmly 50 clamped.

These objects are attained by providing tandem cylinders having a common piston, together with a valve for controlling the distribution of the motive fluid to either one or successively to 55

both of the cylinders. When motive fluid is admitted into the forging cylinder the piston is forced down, bringing the forging dies, or the element carried by the die blocks, into coaction upon the steel, and in such operation motive fluid is prevented from entering the second fluid operated tool. After the forging operation has been performed, and the movable die restored to its elevated original position by motive fluid, in clamping the steel, the operator moves the control valve to such a position as to permit motive fluid to first enter the forging cylinder, moving the piston down, and then moves the valve to its second position permitting additional motive fluid to enter the clamping cylinder and be active upon the common piston, increasing the active clamping force upon the steel. A portion of this additionally motive fluid is conducted through a passageway from the interior of the 20 clamping cylinder to the second fluid operated tool. This passageway opens into the clamping cylinder in such a relation with the piston as to insure, when rapid movement of the control mechanism occurs, first, the admission of motive fluid into the forging cylinder, second, the admission of motive fluid into the clamping cylinder, and finally, the flow of motive fluid from the clamping cylinder to the second fluid operated tool.

30 It is of course understood that this piston controlled passageway may open into the clamping cylinder at any point within the pressure area of the cylinder, the salient point of the invention residing in the fact that the flow of motive fluid to the second fluid operated tool, the dolly hammer, does not take place until the steel has been firmly clamped.

Referring to the drawings in detail, the numeral 11 indicates a cylindrical base including a bottom wall 12 and an outwardly extending annular flange 13, having at spaced intervals thereabout openings 14 for the reception of bolts, by which the base may be secured to a suitable foundation. Disposed horizontally within the base 11, and approximately midway thereof is a wall 15, the central portion of which is provided with an upstanding cylinder 16, the upper end being connected by a second horizontal wall 17 to the upper end of the cylindrical wall of 50 the base. The structure thus described serves to divide the base into two chambers 18 and 19, the former constituting a motive fluid reservoir, while the latter, substantially annular, as shown in Figure 3, constitutes an exhaust receiving chamber, hereinafter more fully described.

Within the chamber 19, and formed integrally with the wall 15 and the cylinder 16 is an upwardly inclined brace 20 serving as a reinforced element for the structure, and at the same time constituting a baffle wall for breaking up the exhaust passing thereover, as will be described later on. Positioned approximately diametrically opposite the brace or baffle wall 20 is a vertical wall 21 extending from the lower wall 15 to the upper wall 17 and from the cylinder 16 to the base wall, closing the annular compartment at that point, see dotted line in Figure 6. The upper wall 17, as shown in Figure 3, is provided with diametrically opposite openings 22, the purpose of which will be described more fully hereinafter.

The lower chamber or reservoir 18 receives motive fluid brought to the machine through a pipe 23 screwed into a supply passage 24 opening into the reservoir.

The top of the base 11 is provided with an outstanding flange 25, having at spaced intervals suitable openings, and positioned upon the flange and secured thereto by side rods 26 passing through these openings is a cylinder 27. 5 The rods 26 are enclosed within vertical ribs formed exteriorly of the cylinder wall. This cylinder 27 has in its lower portion a vertically disposed piston chamber 28, and above the chamber 28 and formed in the cylinder 27, is 10 an upper piston chamber 29 of a smaller diameter than the piston chamber 28, and having direct connection herewith.

Movable vertically in the piston chambers 28 and 29 is a stepped piston body 30, preferably of a single piece, the lower and larger diametrical portion 31 of said body operates in the chamber 28, and has an upper fluid pressure engaging surface 32. The smaller and upper portion of the body 30 forms a piston 33 operating in the smaller piston chamber 29 and having an upper pressure engaging surface 34. Formed centrally of the lower face of the body 30 is a depending piston 35 operating within the upstanding cylinder 16. The piston 35 acts 25 in opposition to the pistons 31 and 33, as its lower face is constantly engaged by motive fluid contained in the chamber 18.

Mounted on the top of the cylinder 27 is a cylinder head 36, secured to the cylinder 27 and base by the side rods 26, and constituting what will hereinafter be referred to as a lower die block. The die block 36, as shown more particularly in Figures 2 and 3, is provided with a plurality of die seats, one being shown at 37 for the reception of a suitable die 38, likewise shown in Figures 2 and 3.

The die block 36 is provided with a rearwardly extending armor bracket 39 constituting a support for the second fluid operated tool or dolly 40 hammer 40, having at its front end a steel upsetting and forming dolly 41.

Positioned over the die block 36 is a movable die block 42, the underface of which is provided with a plurality of die seats, one of which is 45 shown at 43 to receive a die 44 intended to coact with the die 38 positioned in the head 36.

The movable head 42 is mounted upon the ends of spaced bolts 45, slidably mounted in the head 36, and having their lower ends fixed in 50 the piston body 30. The bolts 45 have spacing sleeves 46 interposed between the upper piston surface 34 and the movable die block 42, thereby maintaining the movable die block in a fixed relation with respect to the piston body 30. 55

Motive fluid from any suitable source is delivered into the reservoir 18 of the machine through the pipe 23 and the supply passage 24 formed in the rear of the reservoir. Motive fluid thus supplied acts constantly against the lower 60 face of the piston 35 tending to maintain it, and the die block 42 connected thereto, in an elevated position.

Formed in the wall of the base 11 and extending upwardly from the reservoir 18 is a fluid 65 passageway 47, communicating with a second passageway 48 formed in the wall of the cylinder 27, the latter leading to an annular chamber 49 formed around a removable valve cage 50, pressed into a valve casing 51, detachably connected by bolts 52 to a flat surface 53 formed upon the side wall of the cylinder 27.

At one side of the chamber 49 is an annular groove 54, and beyond the groove 54 is another annular groove 55, all being clearly disclosed in 75

Figure 6. The groove 54, as shown in Figure 8, communicates with a vertical passageway 56, formed in the wall of the cylinder 27, opening into the top of the piston chamber 28, permitting motive fluid when passing therethrough to impinge upon the pressure engaging surface 32 constituting the upper face of the piston 31. The annular groove 55, as shown in Figure 9, is in communication with a second passageway 57, opening into the top of the smaller piston chamber 29 and above the pressure surface 34 of the piston 33. The annular chamber 49 and grooves 54 and 55 have communication with the interior of the valve cage 50 through ports 58. To control the distribution of motive fluid from the annular chamber 49 to the grooves 54 and 55 there is positioned within the cage 50, for slideable movement, a plunger valve 59 having a centrally reduced neck 60, and end heads 61. The valve 59 is connected by a link 62 to a hand actuated lever 63 pivoted at its lower end, as shown at 64, to a depending bracket 65 formed integral with the valve casing 51. To prevent accidental movement of the hand lever there is provided an encircling guard 66 secured to the machine by the bolts 52 serving to connect the valve casing 51 thereto. The guard 66 has pivoted in its front portion a hook 67 adapted to engage a pin 68, carried by the lever 63 to lock the lever and valve in an off position.

Communicating with the interior of the smaller piston chamber 29, as shown in Figure 4, is a passageway 69, having screwed therein a nipple 70 which extends through the wall of the cylinder 27 and has connected thereto a flexible conduit 71 leading to the intake port 72 of the second fluid operated tool or dolly hammer 40 mounted upon the outer end of the bracket 39. It will be observed in Figure 4 that the passage 69 opens into the interior of the piston chamber 29, and it will thus be evident that when additional motive fluid is admitted into the cylinder, through the movement of the control valve 59, it will pass on to the dolly hammer cylinder, thus setting this unit into operation and performing its intended work upon the steel. This arrangement permits the operation of the dolly hammer only at such periods as when the steel or work is securely clamped by both pistons 31 and 33. The passage 69 is closed completely by the piston 33 when the die block 42 is elevated.

As shown in Figure 5, the dolly hammer cylinder supporting bracket 39 has its upper face concaved longitudinally, as shown at 73 to receive the convexed face of the dolly hammer cylinder base 74. The base 74 is provided on opposite sides with longitudinal flats 75, the upper faces of which are engaged by the hooked end 76 of a yoke member 77, resiliently connected to the bracket 39 for vertical movement by bolts 78, and locked in its lowermost or holding position by a locking screw 79. With this structure all that is necessary to move the cylinder 40 longitudinally of the bracket 39, is to loosen the locking screw 79, and by reason of certain resilient elements carried by the bolts 78, the yoke 77 will be moved upwardly, releasing its binding action upon the flats 75 of the dolly cylinder base.

Assuming that motive fluid is supplied to the reservoir it will be evident by referring to Figures 1 and 2 that it has constant access to the interior of the upstanding cylinder 16, and

therefore constantly bears against the lower face of the piston 35 maintaining the piston, and the die block 42, moved thereby, upwardly. The diameter of the piston 35 when acted upon by the motive fluid, is sufficient to move with it the piston body 30 and the upper die block 42.

Should the control valve 59 be in its closed position, motive fluid in the reservoir 18, passages 47 and 48, and annular chamber 49, is held against distribution to the various ports formed in the valve casing by the heads of the valve. However, movement of the valve 59 to the position shown in Figure 6, permits motive fluid to flow from the annular chamber 49 through the ports 58, around the reduced neck 60 of the valve, through the ports 58 of the valve cage into the annular groove 54 from which it passes through the passageway 56 into the lower or larger piston chamber 28 where it engages the upper pressure surface 32 of the piston 31, moving the piston body downwardly, and at the same time moving the movable die block 42 down into coacting relation with the lower die block 36. Due to the enlarged area of the pressure engaging surface 32 over that of the return piston 35, fluid will move the piston body 30, and the die block 42, down into contact with the lower die block 36 with sufficient force for forging and shaping the work. Leakage of motive fluid past the piston 31 is permitted to escape through the openings 22, arranged in the wall 17, into the chamber 19 and finally to atmosphere as will be apparent later on in the description. By rapid reciprocation of the valve within certain limits, sufficiently to form connection between the chamber 49 and the groove 54, and alternately open the groove 54 to atmosphere through the end of the valve as hereinafter described, the upper die block can be made to reciprocate rapidly to impart a series of blows in the forging or shaping operation of the work.

Following the forging or shaping operations should the operator desire to firmly clamp the steel or work between the stationary die block 45 36 and the movable die block 42, so that it might be further worked upon by the dolly 41, actuated by the hammer 40, the valve 59 is moved to the second of its functioning positions, permitting the continued flow of motive fluid as described above and also the passage of motive fluid from the annular chamber 49 through the ports 58, around the reduced neck 60 of the valve, and through the ports 58 to the second annular groove 55 from which it passes through the passageway 57, as shown in Figure 9, to the upper face of the smaller piston 35, impinging upon the pressure surface 34, thereby giving to the piston body 30 the maximum downward pressure equivalent to the pressure of the fluid bearing upon both piston areas 32 and 34. After or during the admission and expansion of motive fluid in the chamber 29, a portion passes therefrom, through the passageway 69 and conduit 71, to the dolly hammer 40, setting it in operation to act upon the work clamped between the two die blocks. Upon the movement of the actuating lever 63 to the left the valve is, of course, moved backwardly cutting off the supply of motive fluid to the annular groove 55, and as the head 61 of the valve 59 moves over the groove 55 it is obviously opened to atmosphere, thus permitting the exhaust of motive fluid from the piston chamber 29. A further backward movement of the valve 59 per-

mits the exhaust from the piston chamber 28 to pass to atmosphere in a like manner. Upon the completion of the exhaust from both chambers 28 and 29, the piston 35 is permitted to act, 5 elevating the body piston 30 and the upper die block 42.

To muffle the exhaust passing out of the cylinders 28 and 29, together with that constantly passing from the dolly hammer 40 when in operation, the chamber 19 formed in the base 11, 10 is used as an exhaust chamber into which the exhaust is admitted and permitted to expand prior to its admission to atmosphere.

As shown in Figures 2 and 3, the chamber 19 is provided with an exhaust inlet 81, and an 15 exhaust outlet 82 adjacent thereto, but separated by the wall 21 formed in the chamber. It is evident that upon the admission of the exhaust through the inlet 81 it enters into the large annular chamber 19 where expansion takes place, 20 breaking it up sufficiently to muffle the sound prior to its admission to atmosphere. After the exhaust has entered into the chamber 19 it seeks its way around the annular chamber 25 and out to atmosphere through the port 82 in the rear of the machine.

Extending upwardly through the wall of the base 11 is a passageway 83 communicating with a similar passageway 84 formed in the wall of 30 the cylinder 27. This vertical passageway 84 communicates intermediately of a horizontally disposed passageway 85 formed within the wall of the cylinder 27, see Figure 6. One branch 86 leads to an exhaust chamber 87 formed in the 35 valve casing 52 and in the rear of the control valve. The other branch 88 communicates with a second vertically disposed passageway 89, likewise formed in the wall of the cylinder 27. This passageway 89 is in communication with a passageway 90 formed within the bracket 39, opening into an exhaust chamber 91 in the base of 40 the dolly hammer cylinder 40, and into which exhaust from the hammer cylinder is permitted to pass during its operation.

From the foregoing it will be evident that 45 during the operation of the dolly hammer, exhaust therefrom passes from the cylinder into the exhaust chamber 91, through the passageways 90, 89, 88, 84, and 83, and port 81 into 50 the exhaust chamber 19, whereupon it will be broken up prior to its admission to atmosphere through the outlet port 82. In the operation of the sharpener it will be evident that when the control valve 60 is moved to such a position 55 as to permit the motive fluid from either or both piston chambers 29 and 30 to exhaust, this extra fluid will pass through the rear of the valve cage into the chamber 87, from whence it flows to the horizontal passageway 86 and into 60 the vertical passageways 84 and 83, entering the chamber 19 through the port 81. Following its entrance into the chamber 19 it will be broken up in the manner herebefore described. By reason of the openings 22 formed in the upper 65 wall 17 of the chamber 19 the exhaust during its expansion engages the under face of the piston body 30, acting thereupon to assist the piston 35 in return of the die block 42 to its elevated position.

To lubricate the machine the chamber 18 not 70 only serves as a reservoir for motive fluid, but as a lubricant container, and in view of the elevated position assumed by the supply passage 24, lubricant may be placed within the reservoir 75 through a filling opening closed by a plug 92

until it assumes a level indicated by the line "A" in Figure 2. To saturate the incoming motive fluid there is provided a nozzle 93 extending vertically, and transversely, of the passage 24. The nozzle 93 is provided with suitable passages 5 so that as motive fluid passes around its body a suction may be created therethrough, drawing up lubricant from the bottom portion of the reservoir and discharging it into the line of flow. Motive fluid thus saturated with lubricant 10 passes upwardly to the control valve and hence into the several piston chambers and dolly hammer cylinder, depositing in each a sufficient quantity of lubricating oil.

To provide sufficient oil upon the bolts 45 15 carried by the piston body 30, and extending upwardly through the die block 37, the upper surface of the movable die block 42 has formed centrally thereof a lubricant well 94, closed at its upper end by a plug 95. The lower end of 20 this well 94 has communicating therewith a plurality of upwardly diverged passageways 96 which serve to convey lubricant from the well 94 to the rods 45, where it ultimately passes down and lubricates sufficiently the wearing surfaces of the rods and sleeves 46.

As shown in Figure 2, the bottom wall 12 of the base is slightly inclined, and at its lowermost portion there is provided a drain opening 97, closed by a removable plug 98.

From the foregoing it is thought that the construction, operation and many advantages of the herein described invention will be apparent to those skilled in the art without further description, and it will be understood that various changes in the size, shape, proportion and minor details of construction may be resorted to without departure from the spirit or sacrificing any of the advantages of the invention.

What I claim is:

1. A drill sharpener comprising a pair of work fabricating units coactive at times upon the work, one of said units including a fluid actuated motor having a piston, a work engaging member carried by the piston and movable to at least two functioning positions, means controlling the flow of fluid to the motor, a fluid passageway from the motor to the other of said units, and said piston when in one position permitting the flow of fluid through said passageway.

2. A drill sharpener comprising a pair of fluid actuated work fabricating units coacting upon the work, one of said units including a piston having two correspondingly positioned surfaces engageable by active fluid, means permitting the passage of fluid to said surfaces independently to one and successively to both, a fluid passageway leading from one unit to the other, and said piston when moved by fluid active upon one surface exposing the passageway to the other unit for the passage of a portion of the operating fluid subsequently engageable with the other of said surfaces.

3. A forging machine including a fluid actuated work fabricating unit having a piston, a member carried thereby and engageable with the work for performing several operations thereupon, a second fluid actuated work fabricating unit coacting with the first unit for performing jointly one of said operations, a valve mechanism 65 controlling the flow of fluid to the first unit to impart motion to the piston and movable member for performing its several operations, a fluid passageway leading from the piston contained unit to the other unit, said passageway being 70

opened and closed by said piston and said piston and movable member when performing one of said operations permitting the unrestricted flow of fluid through said passageway to the other work fabricating unit during the performance of another operation.

4. A forging machine including a pair of opposed work forming dies, one of which is movable with respect to the other, a piston connected to a movable die and positioned within a cylinder, said piston having separate faces engaged by motive fluid admitted into the cylinder, a work engaging element positioned upon the machine for action upon the work clamped between the dies, said element being actuated by fluid admitted thereto through a passageway leading from the cylinder, a valve mechanism controlling the flow of fluid to the faces for varying the force exerted upon the work, and said piston when moved by fluid active against one face uncovering the passageway permitting a portion of the fluid when active against the other face to pass to the second work engaging element.
5. A drill sharpener comprising a pair of fluid actuated work engaging elements adapted to contact at times upon the work, one of said elements including a pair of cylinders and a piston common to both, said piston having a head in each cylinder and when moved by fluid active thereupon capable of performing at least two distinct functions upon the work, a passageway connecting one of said cylinders with the other

of said elements, a valve movable to two positions for controlling the flow of fluid to the cylinders, said valve when moved to one position permitting a flow of fluid upon the head in one cylinder for moving the piston to perform one operation and when moved to its other position permitting a flow of fluid upon the heads in both cylinders for increasing the active force upon the piston during the performance of its second operation, and said piston during its movement to perform the first said operation uncovering the passageway leading to the other of said work engaging elements for the passage of fluid to the other of said elements when performing its second operation.

6. A drill sharpener comprising a pair of fluid actuated work engaging elements one of which includes a pair of cylinders, a common piston having a head in both cylinders, a die block integral with said piston, said piston moved by fluid active upon the heads to bring the die block in contact with the work for forging and clamping operations, the other of said elements operating upon the work when clamped by the first element, a passageway connecting one of said cylinders with the other of said elements, a valve controlling the flow of fluid to one cylinder for the forging operation and to both cylinders for the clamping operation, and said piston during the clamping operation permitting the flow of fluid from one cylinder to the other of said work engaging elements.

GUSTAV C. PEARSON.
